CORE-DRILL.

No. 821,130.

Specification of Letters Patent.

Patented May 22, 1906.

Application filed October 17, 1905. Serial No. 283,191.

To all whom it may concern:

Be it known that we, JOHN MORRIS SMITH, of Reynoldsville, in the county of Jefferson, and ROBERT M. DOWNIE and FREDERICK W. RANSOM, of Beaver Falls, in the county of Beaver, State of Pennsylvania, citizens of the United States, have invented a new and useful Core-Drill, of which the following is a specification.

10 This invention relates to means for extracting solid cores from bore-holes.

It is well known that the most economical method of making a large bore-hole in the earth is by means of a percussion chisel-drill 15 working with a vertical reciprocatory motion striking the rock at the end of each descent; but such chisel-drill is not best adapted for exploring certain kinds of mineralized formations owing to the fact that the drill has a 20 tendency to cut up and pulverize the rock through which it passes.

The primary object of the present invention is to provide a device which can be operated by any machine that drills by vertical 25 percussion blows and which will secure a core without breakage, said device being of a nature that will permit it to be substituted for the ordinary bit.

A further object is to provide a core-drill in 30 which different styles of bits or cutters can be employed that are adapted to the various formations to be found.

Still another object is to provide a reciprocatory or percussion core-drill which is operative without the necessity of venting the 35 same, means being provided for opposing the resistance due to the confined and compressed air contained in the drill.

An embodiment of the invention that is at 40 present considered the preferable one is disclosed in the accompanying drawings; wherein—

Figure 1 is a sectional view through the drill, portions of which are broken away, said 45 view showing the core-holder as forced back into the casing against the action of the weight and the tension of the spring. Fig. 2 is a detail sectional view, on an enlarged scale, through the lower portion of the same including the cutter-head. Fig. 3 is a bottom plan view of said cutter-head. Fig. 4 is a bottom plan view of the cutter-head sleeve.

Fig. 5 is a top plan view of the keeper constituting a part of the head. Fig. 6 is a plan view of the ring-axle. Fig. 7 is a detail sectional view, on an enlarged scale, through the swivel connection between the core-barrel and weight. Fig. 8 is a bottom plan view of the carrier - collar and antifriction - rollers. Fig. 9 is a sectional view on the line 9 9 of Fig. 7. Fig. 10 is a detail sectional view through the lower portion of the core-barrel, showing the retaining-tongues. Fig. 11 is a sectional view through a different form of bit or cutter. Fig. 12 is a bottom plan view thereof. Fig. 13 is a sectional view of a modified form of cutter, and Fig. 14 is a plan view of the same. Fig. 15 is a sectional view of still another form of cutter, and Fig. 16 is a plan view thereof.

Similar reference-numerals designate corresponding parts in all the figures of the drawings.

In the embodiment of the invention disclosed in the first ten figures a tubular imperforate drill-stem 17 is employed, into the upper end of which is screwed an attaching-head 18, that completely closes said upper end. The head projects above the stem, being provided with an angular portion 19 for the reception of a wrench and terminating at its upper end in an upstanding screw-shank 20, by means of which the tool can be connected to the common jars or rope-socket of a set of percussion drilling-tools. The lower end of the tubular stem carries a bit or cutter, which in the present and preferred embodiment consists of a sleeve 21, exteriorly threaded upon the lower end of the stem and depending beneath the same, being provided with a bore 22 of less diameter than the bore of the stem, thereby forming a shoulder 23. The sleeve 21 is provided in its lower end with an annular seat 24 and with transverse sockets 25 that intersect 95 said seat. These sockets receive cutting rollers or wheels 26, having sharpened peripheral cutting edges 27 disposed radially to the axis of the stem, the wheels having a diameter greater than the thickness of the 100 sleeve, and thus projecting beyond the inner and outer faces thereof. The said cutter-wheels are journaled upon an axle that is in the form of a split ring 28, which can be

spread apart sufficiently to receive said wheels, the ring being disposed in the seat 24 and held in place by a keeper-collar 29, having outturned curved ears 30, that extend 5 over the ring between the wheels. The collar 29 fits within the lower end of the sleeve, which is counterbored for the purpose and is held in place by rivets 31 or other suitable fasteners.

10 Slidably mounted within the stem 17 is a core-holder in the form of a barrel or tube 32, the lower end of which is normally located in the sleeve 21, said barrel sliding freely through the sleeve and longitudinally within the stem 17. The lower end of the barrel is open, and contiguous to said lower end are inwardly and upwardly extending core-retaining tongues 33, the upper ends of which are preferably sharpened. The upper end of the 20 core-barrel is completely closed by a cap 34, into which said barrel is detachably threaded, said cap constituting one of a pair of relatively rotatable swivel members, the other member comprising a spindle 35, that is journaled in the cap and is carried by the lower end of a weight 36, that extends longitudinally in the upper portion of the stem 17. The cap 34 rests upon a thimble 37, held in place by a nut 38 and washer 39, the former 30 being preferably locked by a suitable pin 40.

Located upon the spindle 35 above the cap is a carrier-collar 41, against which the weight 36 bears. This carrier-collar is provided with a series of recessed seats 42, in which are journaled antifriction-rollers 43, mounted on the carrier, which rollers bear against the inner face of the drill-stem 17 and are located directly adjacent to the swivel-joint. Between the carrier 41 and cap 34 is arranged a ball-bearing, consisting of a pair of wear-plates 44, located on the spindle 35 and having circular runways 45 on their opposing faces, which runways receive balls 46. A coiled spring 47 surrounds the weight 36 and has its lower end bearing upon the collar 41, while its upper end bears against the lower end of the attaching-head 18, said head, as shown in Fig. 1, preferably having its lower end recessed, as shown at 48, to receive the upper end of the weight, the weight being so disposed that when abutted against said head the lower end of the barrel is located within the sleeve 21 of the cutter-head. This is disclosed in Fig. 1. By reference to Figs. 1, 7, 55 and 9, it will be noted that the lower edge of the barrel-cap 34 has a series of sockets 49. These sockets are arranged to receive the head-lugs 50 of holding-pins 51, located in the sleeve 21 of the bit.

60 Instead of the bit above described different types may be employed for different kinds of materials. Thus in Figs. 11 and 12 a sleeve 52 is employed, the upper end of which is interiorly threaded, as shown at 53, so that it may be screwed upon the drill-stem

17, the lower end having a number of radial cutting edges 54. Still another form is illustrated in Figs. 13 and 14, the sleeve 55, disclosed therein, having a saw-tooth construction—that is to say, the lower teeth 56 are set alternately outward and inward. Still another type is shown in Figs. 15 and 16, wherein the sleeve 57 has but two teeth or cutting edges 58.

175 In prospecting with this structure the principal portion of the drilling is performed by means of the common percussion-drill, such as is used for drilling oil and water wells. When, however, the mineralized or other formation of which a sample is desired is 80 reached, this common percussion-drill is detached from the drilling-tools, and the tool disclosed is substituted in its place. During the lowering thereof into the bore-hole the core-barrel 32 will be projected from the 85 lower end of the stem, because of the weight 36 and spring 47, said barrel being supported by the cap resting upon the shoulder 23 of the cutter-head. As soon as the bottom of the hole is reached the barrel will be forced 90 back into the stem and the drill is then operated in the ordinary manner. It will be apparent that a core will be formed by the cutters, and this core will enter the lower end of the barrel, the spring continuously pressing 95 the core-barrel against the bottom of the bore-hole or, in other words, forcing the barrel downwardly over the core as the latter is formed and preventing the barrel being raised by frictional contact with the hollow 100 drill-stem as the latter rises between strokes. In case the spring is not sufficient to cause the downward feed of the barrel it will be seen by reference to Fig. 1 that the head 18 will strike the upper end of the bar 48, and thus the 105 weight of the string of tools will be brought to bear upon said barrel. As the spring has a contact at its upper end with the attaching-head and as the antifriction-rollers 43 engage the stem, the tendency of the same is to 110 revolve with the stem as the drilling-tools are turned; but because of the swivel connection and the roller-bearing the core-barrel will remain stationary and the danger of twisting the core off at the bottom of the hole, and thereby injuring or destroying it, is eliminated. It will be observed that there are no vents either in the core-barrel or in the stem, an important feature in a structure of this kind, and because of this there is a liability of air being confined within the closed part. The spring, however, serves to hold the barrel down against the pressure of the air and prevents the same moving upwardly upon 115 the upstrokes of the tool.

120 The tongues 33 of the barrel slide freely down upon the core as it is made, but have a tendency to dig into and catch the core when the drilling-tool is drawn from the well. The core will thus be broken off and retained in 125 130

the barrel until the surface is reached. During its upward movement the cap 34 will rest upon the shoulder 23 of the cutter-head, so that the barrel 32 with its contained core will be projected from the stem. To remove the core from the barrel after the same has been withdrawn from the bore-hole, it is first necessary to detach the barrel. This is readily accomplished by rotating the same, whereupon the seats 49 will be brought into alignment with the head-lugs 50 of the pins 51, and said head-lugs will enter the seats. The cap will thus be held against further rotation, and upon the continued rotation of the barrel said barrel will unscrew from the cap and the core will thus be easily removed.

We are aware that a hollow drill-stem inclosing a core-barrel is not new; but those formerly devised were so constructed that the water, which is usually unavoidably present in the bore-hole, always gained access to the core, often destroying it. If the water is not present from a natural source, it must be supplied and either poured into the bore-hole around the drill or forced down a tubular rod to the inside of the hollow barrel. It will be noticed that the drill here shown excludes the water even under great pressure in the following way: When the tool is ready to let down the bore-hole, the core-barrel will be full of air and will project almost its full length below the cutter-head. When the lower end of the core-barrel in its descent reaches the water, the air will be sealed within it, and when the cutter-head also reaches the water-level the hollow drill-stem, also full of air, will be sealed against escape. Then when the core-barrel is later pressed against the bottom of the bore-hole it will be forced back up the hollow stem, adding its contents of air to that already in the hollow stem, and thus creating a pressure equal or greater than the pressure of the water. In this way the water is practically excluded from the inside of the hollow drill-stem. This feature of the invention has another very important use—namely, to prevent the cuttings from working up between the core-barrel and the hollow stem to clog it—the entrance of the water and cuttings being prevented by the said pressure of the air within the hollow stem.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described our invention, what we claim as new, and desire to secure by Letters Patent, is—

1. The combination with a tubular reciprocatory drill-stem having a percussion-cutter at its lower end, of a tubular core-holder located within the stem and having a free longitudinal movement in the same, the lower portion of said tubular core-holder being movable freely through the percussion-cutter, and a spring engaging the holder and urging the same through said percussion-cutter. 75

2. The combination with a tubular reciprocatory drill-stem having a completely-closed upper end and an open lower end, of a percussion cutter-head surrounding said lower end, a tubular core-holder located within the stem and having a free longitudinal movement therein, and a spring engaging the holder and urging the same through the said cutter-head. 80

3. The combination with an imperforate stem-tube, of an attaching-head completely closing the upper end thereof, a percussion drill-head sleeve secured to the lower end of the tube, a freely-movable core-barrel longitudinally slideable in the stem-tube and movable through the sleeve, and a coiled spring interposed between and bearing against the attaching-head and barrel to urge the latter outwardly through the drill-head sleeve. 90

4. The combination with a tubular drill-stem, of a longitudinally-movable swivel therein, said swivel comprising relatively rotatable members, a core-holder carried by one member, and a spring associated with the other member to urge the holder over a core. 95

5. The combination with a tubular drill-stem, of a longitudinally-movable core-barrel located therein, and a spring having a swiveled bearing upon the core-barrel. 105

6. The combination with a tubular drill-stem, of a longitudinally-movable swivel therein comprising relatively rotatable upper and lower members, a tubular core-barrel depending from the lower member, and a coiled spring extending above the swivel and bearing downwardly thereupon. 110

7. The combination with a tubular drill-stem, of a longitudinally-movable core-barrel located therein, a cap carried by the upper end of the barrel and constituting a swivel member, another member including a spindle journaled in the cap, and a coiled spring bearing upon said other member. 115

8. The combination with a tubular drill-stem, of a core-holder movable therein, a weight having a swivel connection with the core-holder, and a spring associated with the weight. 120

9. The combination with a tubular reciprocatory drill-stem carrying a percussion-cutter at its lower end, of a core-barrel longitudinally slideable in the stem, a weight having a swivel connection with the upper end of the barrel, and a spring surrounding the 125

- weight and bearing against the swivel connection.
10. The combination with a drill-stem, of a core-barrel longitudinally movable therein and having a cap at its upper end, a weight located above the barrel and having a stem journaled in the cap, and a spring coiled about the weight and urging the core-barrel downwardly.
11. The combination with a tubular drill-stem, of an attaching-head secured to the upper end thereof and closing the same, a percussion drill-head secured to the lower end of the stem and having an opening therethrough, a tubular core-barrel slidably mounted in the stem and movable through the opening, a cap secured to the upper end of the barrel, a weight swiveled on the cap and located between the barrel and attaching-head, said weight being adapted to engage with said attaching-head, and a spring surrounding the weight and bearing against the attaching-head, said spring urging the core-barrel downwardly.
12. The combination with a stem, of a core-holder movably associated therewith, means for effecting the downward movement of the holder, said means having a swivel connection with the holder, and antifriction-rollers located contiguous to said swivel connection.
13. The combination with a tubular stem, of a core-holder longitudinally movable therein, a weight for moving the holder downwardly in the stem, said weight having a swivel connection with the holder, and antifriction-rollers carried by said swivel connection.
14. The combination with a stem, of a core-holder movably associated therewith, a weight having a swivel connection with the upper end of the core-holder, a carrier mounted on the swivel connection, and rollers journaled on the carrier and operating against the stem.
15. The combination with a stem, of a core-holder movably associated therewith, a weight having a swivel connection with the upper end of the core-holder, a carrier mounted on the swivel connection, rollers journaled on the carrier and operating against the stem, and a ball-bearing interposed between the carrier and holder.
16. The combination with a tubular drill-stem, of an attaching-head secured to the upper end thereof, a percussion cutter-head sleeve secured to the lower end of the stem, a tubular core-barrel slidably mounted in the stem and arranged to move through the cutter-head, a cap carried by the upper end of the barrel, a weight located within the barrel and having a spindle journaled in the cap, a carrier-collar mounted on the spindle and having recessed seats, rollers journaled in the seats and bearing against the drill-stem, and a spring surrounding the weight and bearing against the carrier-collar.
17. The combination with a drill-stem and core-holder, of a cutter carried by the lower end of the stem and including a series of rollers having sharpened peripheral edges.
18. The combination with a drill-stem and a core-holder, of a sleeve carried by the lower end of the stem and having a series of slots, cutting-rollers located in the slots, journal means for said rollers mounted on the sleeve and a keeper secured to the sleeve and having ears that extend between the rollers and over the journal means.
19. The combination with a drill-stem and a core-holder, of a sleeve carried by the lower end of the stem and having a series of slots, cutting-rollers located in the slots, a ring-axle for said rollers located at the end of the sleeve, and a keeper secured to the sleeve and having ears that extend between the rollers and over the axle to retain the latter in place.
20. The combination with a drill-stem and core-holder, of a cutter comprising a sleeve secured to the lower end of the stem, said sleeve having an annular seat and slots intersecting the same, rollers located in the slots, a ring-axle for the rollers located in the seat, and a keeper extending over the axle.
21. The combination with a tubular stem, of a core-barrel longitudinally movable therein, means detachably associated with the core-barrel for effecting the feeding movement thereof over a core, and a device for holding the moving means against rotation during the detachment of the barrel therefrom, said device being carried by the stem and said means being movable into and out of engagement therewith.
22. The combination with a tubular stem, of a cutter-head carried by the lower end thereof, a lug disposed inside the stem adjacent to the cutter-head, a core-barrel slidably mounted within the stem, a cap screwed upon the upper end of said barrel, said cap having a socket that receives the lug, and means for urging the barrel outwardly to bring the seat of the cap to a position to receive the lug.
- In testimony that we claim the foregoing as our own we have hereto affixed our signatures in the presence of witnesses.
